UNITED STATES PATENT OFFICE.

JOHN B. BOLTON, OF PHILADELPHIA, PENNSYLVANIA, ASSIGNOR OF ONE-HALF TO
JOHN BROMLEY & SONS, INCORPORATED, OF PHILADELPHIA, PENNSYLVANIA, A
CORPORATION OF PENNSYLVANIA.

BOBBIN FRAME FOR LOOMS.

Application filed September 21, 1921. Serial No. 502,152.

To all whom it may concern:

Be it known that I, JOHN B. BOLTON, a citizen of the United States, residing in the city of Philadelphia, State of Pennsylvania, ⁵ have invented certain new and useful Improvements in Bobbin Frames for Looms, of which the following is a specification, reference being had to the accompanying drawings, forming a part hereof.

10 My invention relates to means for detachably supporting the rotatable bobbins on which the yarn is wound, for use in the loom, these means being commonly called a bobbin frame which, in addition to providing ¹⁵ bearings for rotatably supporting the bobbin comprise tubular eyes for guiding the yarn to the loom, the bobbin frame itself being detachably supported on the loom.

My invention has for its objects to reduce ²⁰ the cost of construction of the bobbin and to strengthen it, by eliminating the spring-actuated stub shaft at one or both bored-out ends of the bobbin, as it is now commonly made, and to supply a different ²⁵ mechanical element, to perform its function, but instead of making such functional substitute an element a part of the bobbin, as before, I leave the bobbin solid, without end borings and with fixed bearing shafts, ³⁰ and construct the resilient bearing therefor as an element forming a part of the bobbin frame, and of such character as to strengthen the latter and make it more durable, and the insertion and removal of ³⁵ the bobbin easier to manipulate; and in other respects increase the efficiency of the bottom frame and its bobbin, as an operative unit.

To these ends my invention consists of the ⁴⁰ combination of elements hereinafter described, the novel and characteristic features being as stated in the appended claim.

In the drawings illustrating the invention Fig. 1 is a side elevation from the front of ⁴⁵ the device, partly broken away in the centre. Fig. 2 is a sectional view thereof. Fig. 3 is a left hand end view of the device of Fig. 1, looking in the direction of the arrow line 3—3. Fig. 4 is a left hand end view of the ⁵⁰ device of Fig. 1 looking in the direction of the arrow line 4—4, which is the opposite of that of the line 3—3. Fig. 5 is a right hand end view of the device of Fig. 1 looking in the direction of the arrow line 5—5. The

bobbin or spool is indicated at 1, having the ⁵⁵ usual button or end pieces 2, each carrying a stub shaft 3 consisting of the projecting end of a comparatively long and heavy steel nail ⁶⁰ 3^a driven through the end piece 2 into the body portion 1 of the spool. These projecting ends serve as bearing shafts for the spool, and by which the latter is supported rotatably.

The bobbin frame, on which the bobbin is rotatably supported, consists of a hard ⁶⁵ wood bar 4, of slightly greater length than the bobbin, on the upper face of which is mounted, at each end, a flat bar spring 5, 5, to support the bobbin vertically and maintain it in a horizontal plane, so that it will ⁷⁰ run true and also be maintained by its stub shafts 3 in a bearing therefor mounted on each end of the bobbin frame hereinafter described.

In both the old art and in the new as improved by me, the bearing member consists, primarily, of a metal plate having a base flange 6 and, at right angles thereto, a vertically disposed body portion 7, both of them of a width approximately equal to the ⁷⁵ width of the wooden base bar 4, and both of them secured to the base and end of the frame body 4, by screws 4^a or equivalent means. The vertical body portion 7 of this plate is given an outwardly inclined bend, at its ⁸⁰ upper end, terminating in a vertical flange or end piece 7^a. The portion 7^a which is thus bent outwardly is slotted, as indicated in the several figures, more particularly shown in Fig. 3, this for the purpose of allowing a flat spring 8 to pass through it and to have a limited amount of play therein. This spring is secured fast at its lower end, as by screws 8^a, to the extreme end of the ⁸⁵ frame bar 4, and is given an inwardly inclined bend, as at 8, terminating in an inward bend to form a manually operated hook 8^a. The function of this fixed element 7 is primarily to support means operable to detachably support the bobbin in the frame. ⁹⁰ On the outer lower face of the frame body 4 is mounted, as usual, the row of tubular eyes 9, through which the yarn threads on the bobbin are led to the appropriate parts of the loom, as usual.

⁹⁵ ¹⁰⁰ ¹⁰⁵ These bobbins are subjected to rather hard usage, in the mill, require detachment for refilling with yarn, and replacement on the

2
bobbin frame for use in the loom, and the boring out of the end of the bobbin to mount therein the resiliently movable shaft 15 and its spring adjuncts as has been the practice heretofore materially weakened the bobbin at that point, causing frequent breaking, which made expense, and this, in addition to the initial cost of construction.

My invention overcomes both these sources of expense, and by the following means, namely: I dispense with boring out one end of the bobbin, and with the resilient stub shaft, its spring and adjuncts, and I construct the bobbin with fixed stub shafts 3, at both ends. I dispense with the inwardly inclined bend or recessed bearing-lip 10, which is part of the fixed element 6-7, and substitute a spring-bearing 14 for the bobbin shaft instead of such fixed bearing 10; but I retain all the rest of the member 7 including the recess 7^c therein to allow the spring bearing 14 to pass through it with a guided and limited play therein.

To provide a resiliently movable bearing 14 for the bobbin shaft, I provide a steel spring 14 narrower than the slot 7^c so that the spring 14 may move into and from the slot, One end of which is secured to the end of the bobbin frame, between it and steel bearing frame 7, preferably, as shown on the left hand side of Figs. 1 and 2, and for this purpose I prolong the slot 7^c in the bend 7^a to extend slightly into the vertical body portion 7 of the bearing member, to give a freer movement of the bearing spring 14; though this extension of the slot 7^c is not necessary if the steel spring 14 is passed downward through the slot 7^c and its lower end fastened to the bobbin frame outside the steel bearing body 7.

The resilient bearing spring 14 is supported for a portion of its length by the body portion 7 of the bearing member and it is slightly inclined inwardly towards and ending in a vertical portion 14^a which is

appropriately apertured to supply a bearing for the stub shaft 3 to pass freely through it and be rotatably supported therein. The extreme end of the resilient bearing spring 14 is bent to form an operating finger piece 14^b. This bearing spring may thus be made of very considerable width, giving strength to it, and, if properly tempered to give the requisite resiliency, provides a most convenient means to detachably support the bobbin in the bobbin frame. If desired the same means may be employed at both ends of the bobbin frame, but ordinarily one is sufficient precisely as in the old art one resilient stub shaft was alone commonly used. In addition to the advantage of ease of manipulation, the avoidance of recessing the end of the bobbin and the expense of supplying a resilient stub shaft thereof is entirely saved, and the solid bobbin, of course, much stronger.

Having thus described my invention, I claim:

The combination of a bobbin having a stub shaft projecting from one end thereof, a frame bar having means on one end portion thereof to rotatably support one end of the bobbin, a bearing member projecting from other end portion of the frame bar and having a slot therein, a spring projecting fixedly from the frame bar and having an aperture in its free end portion into which the stub shaft extends, said bearing member supporting said spring for a portion of its length and said spring being narrower than said slot and being movable into the same to move it from the stub shaft to free the bobbin.

In testimony whereof I have hereunto affixed my signature this 12th day of September, 1921.

JOHN B. BOLTON.
